UNITED STATES PATENT OFFICE.

ERNEST N. HUMPHREY, OF NEW BRITAIN, CONNECTICUT, ASSIGNOR TO THE TRAUT & HINE MANUFACTURING COMPANY, OF NEW BRITAIN, CONNECTICUT, A CORPORATION OF CONNECTICUT.

SUSPENDER ATTACHMENT.

1,160,098.

Specification of Letters Patent.

Patented Nov. 9, 1915.

Application filed April 15, 1915. Serial No. 21,530.

To all whom it may concern:

Be it known that I, ERNEST N. HUMPHREY, a citizen of the United States, residing at New Britain, county of Hartford, State of Connecticut, have invented certain new and useful Improvements in Suspender Attachments, of which the following is a full, clear, and exact description.

This invention relates to attachments for 10 suspenders and the like and is designed to provide a tab end attachment of simple construction and easy application, and which may be constructed in a form which will admit the parts to be carried in stock partially 15 assembled, and which will admit of their ready application to webbing when it is desired to make up a particular order of suspenders or the like. It is a well known fact that the rubber in elastic webbing deteriorates with time and exposure to the air. It 20 is also a well known fact that fashions in the webbing of suspenders, etc., change. Consequently it is very desirable to have a fitting which may be manufactured and partially assembled, and which may thereafter be readily applied to the webbing. This enables the cord and other parts of the suspender structure which do not deteriorate by exposure to be at least partially assembled 25 and kept in stock ready for application to the webbing when desired. These and other objects of the invention will be more clearly seen from a reading of the following detailed specification, taken in connection 30 with the accompanying drawing forming a part thereof and illustrating a preferable embodiment of the invention.

In the drawings,—Figure 1 is a view of the back portion of a suspender structure 40 equipped with the fitting of the present invention. Fig. 2 is a vertical section on the line 2—2 of Fig. 1. Fig. 3 is a horizontal transverse section on the line 3—3 of Fig. 1. Fig. 4 is a plan view of the blank of the bar 45 before folding and before insertion within the folded web end.

Referring to the drawings by numerals, 1 indicates the shoulder straps of the ordinary suspender structure and 2 the back strap 50 thereof. These straps are connected by a sliding compensating cord structure or harness 3 the lower terminals of which are

formed into the usual back loops 4 for engagement with the buttons. This cord structure is connected to the shoulder and back strap by means of web end attachments which constitute the subject-matter of the present invention. These attachments, in the case of the ends of the shoulder strap and the lower end of the back strap are provided with a single cord guide while the attachment at the upper end of the back strap is provided with three cord guides, as is usual in a suspender of this character. These attachments are similar in structure 65 except for the provision of the added end cord guides of the three-guide attachment. I will therefore describe this three-guide attachment first, it being understood that the single cord guide is of the same construction 70 save for the additional parts specifically mentioned.

Each attachment comprises a metal bar or plate which is bent upon itself to inclose a portion of a webbing end and is then enveloped within a fold of the webbing end, a portion of this plate being formed to extend through an aperture formed in the webbing to a point beyond the webbing, a cord guide being suitably secured to this extended portion. The blank or piece of sheet metal from which such a plate may be formed is shown in plan view in Fig. 4 of the drawings wherein 5 designates the body portion of the plate having a pointed edge 6 and 80 having its opposite edge slotted to form a tongue 7, which is designed to form a cord guide supporting means. In the type of plate wherein but a single cord guide is employed the plate will terminate in line with 85 the end of the gripping edge 6, as indicated by dotted lines in Fig. 4. Where the plate is to be used for a three cord tube guide as at the upper end of a back strap of a suspender, it will be extended at its ends to 90 form ears 8, which ears themselves will be shaped to provide the end guides for the cord at the sides of the webbing. The blank when in its final form is folded along the dotted lines indicated in Fig. 4, excepting as 100 to the integral extension 7, which part is not folded, but constitutes a projecting tongue extending laterally from the bar to afford a means of connection for one of the guide

tubes as later described. The biting points 6 of the gripping edge are preferably inwardly directed so that they will engage in fabric of webbing which may be held between the folded plate or bar and securely grip the same, as will be hereinafter seen. In the case of the single cord guide attachment, as before stated, there will be no ears 8, consequently the physical omission of this part of the bar is necessary. In other respects the structure and operation is the same. These bars when thus folded may be assembled in bulk ready for application to a webbing end. The cord for the ends of the shoulder strap and back strap is separately assembled, being passed through tubular cord guides 9 of any suitable construction, the ends of these cord guides being held together in any suitable manner over the cord. For instance a tubular rivet may be employed or the metal of the guides may be simply bent together to hold temporarily. Such cord structures having the guides attached thereto may be made in bulk and kept in stock for any length of time. So also may the bars, folded as described.

When it is necessary to make up an order of suspenders the folded bars are attached to the end of the webbing straps as follows: 30 Each end of webbing at the rear ends of the shoulder straps 1 and the upper and lower ends of the back straps 2, adjacent their ends, is provided with an aperture, the latter being located at a predetermined distance 35 from the end. The folded bars 5 are then clamped about the end of the webbing, the prongs 6 biting into the fabric and securely holding the bar thereto. The webbing is then looped about the under face of the 40 folded bar so that the downwardly projecting tongue 7 extends through and beyond the aperture formed in the webbing, the webbing being consequently brought upwardly (as seen in Fig. 2), and stitched to 45 the loop portion above the bar as shown at 10, Fig. 2. The appropriate cord guides 9 may then be pivotally secured to the projecting tongue 7 which will extend beyond the folded webbing end. Such attachment may 50 be made by any suitable means as by a pivot stud, a rivet, etc. The cord guides may be mounted upon opposite sides of the projecting tongue 7, as seen in Fig. 2, as is obvious, or may be previously secured together by 55 tubular rivets and then subsequently pivoted to one face of the tongue extension 7. The ends 8 of the bar are coiled about the cord guide, which extends at the sides of the back strap shown in Fig. 1 to form end 60 cord guides 8^a. These cord guides in the structure shown are rigid with the plate, but it is fully within the spirit of the invention, and it is possible, though not preferable, to substitute a shorter extension for the part 8 65 and to pivotally mount a separate cord

guide, such as those shown at 9, in place of the integral cord guide 8^a.

While the foregoing description is necessarily a detailed one in so far as it concerns the particular embodiment selected for illustration, it is to be understood that in this specification and in the appended claims, terms are used in their descriptive sense and that structural modification is included within their spirit and scope. 75

What I claim therefore and desire to secure by Letters Patent is:

1. In a garment supporter, a folded webbing end having an aperture therein, a bar enveloped within said folded webbing end with a member constituting a permanent part of the bar extending from said bar and through said webbing aperture in the direction of webbing length, and a cord guide carried by said extended member with means for connecting said guide to said extension externally of the fold in said web. 80 85

2. In a garment supporter, a folded webbing end having an aperture therein, a bar enveloped within said folded webbing end, said bar comprising a plate folded upon itself to pinch therebetween the webbing end, and itself inclosed within a fold of said webbing, said plate having an integral projecting portion extending through said webbing aperture, and a cord guide carried by said extended portion and secured thereto externally. 90 95

3. In a garment supporter, a folded webbing end having an aperture therein, a bar enveloped within said folded end and comprising a plate having a toothed edge, folded upon itself to inclose and grip therebetween the webbing end, and itself subsequently enveloped within a fold of said webbing end, 100 105 said plate having an integral projecting portion extending through said webbing aperture, with a cord guide pivotally carried by said extended portion.

4. In a garment supporter, a folded webbing end having an aperture therein, a bar enveloped within said webbing end, said bar comprising a plate folded upon itself to inclose therebetween the webbing end, and itself inclosed between a fold of said webbing, said plate intermediate its length being provided with a projection extending through said webbing aperture in the direction of webbing length, and also having at its ends integral extensions projecting beyond the side edges of said webbing end, with cord guides carried by said intermediate and end extensions of said plate and secured thereto externally of said fold in the webbing. 110 115 120

5. In suspender attachments, a compensating cord harness for the back and shoulder straps of a suspender, said harness having cord guides mounted thereon, and cord supporting bars arranged to be applied to and inclosed within the folded ends of the shoul- 125 130

der and back straps, said bars having integral extending members arranged to project beyond the plane of their respective folded strap ends, said members being arranged to receive and support said cord guides outside of said folded portion with means formed integrally with each of said bars to pinch

upon and hold the end of the piece of webbing.

ERNEST N. HUMPHREY.
